AUTOMATIC GREASE CUP

Filed July 18, 1927

Fig. 1.

Fig. 2.

Fig. 4.

A technical drawing of a circular component. The outer boundary is a thick, hatched line. Inside, there is a dashed circle representing the inner boundary. Two small circles are located on the dashed circle, each with a diameter of 15, labeled '15' with a leader line. In the center of the dashed circle is a small circle with a diameter of 6, labeled '6' with a leader line. A horizontal line extends from the right side of the drawing, labeled '1' at its end, indicating the width of the ring between the outer boundary and the dashed circle. Another horizontal line extends from the bottom right, labeled '16' at its end, indicating the total width of the ring.

UNITED STATES PATENT OFFICE.

LOUIS A. LE DOUX, OF MOUNT ANGEL, OREGON.

AUTOMATIC GREASE CUP.

Application filed July 18, 1927. Serial No. 206,650.

The invention relates to automatic grease cups, and has for its object to provide a device of this character comprising a casing having a cap, which cap is provided with 5 a hollow valve stem, the end of which valve stem cooperates with a port and ports of communication between the interior of the valve stem and the chamber of the casing below a spring pressed piston slidably 10 mounted on the valve stem, thereby allowing grease to be forced into the cup through a valve controlled port and discharged into the cup below the piston without removing the cup.

15 A further object is to thread the cover on the valve casing, and to provide said cover with latching means cooperating with the casing whereby said cover may be adjusted on the casing for varying the position of the 20 valve in relation to the discharge port of the casing, thereby allowing regulation of discharge of lubricant from the cup.

A further object is to interpose a helical spring between the piston and the cap, the 25 convolutions of which will pass into each other, thereby allowing a wide range of movement of the piston and the reception of a maximum amount of lubricant in the cup.

30 With the above and other objects in view the invention resides in the combination and arrangement of parts as hereinafter set forth, shown in the drawing, described and claimed, it being understood that changes in 35 the precise embodiment of the invention may be made within the scope of what is claimed without departing from the spirit of the invention.

In the drawing:

40 Figure 1 is a vertical transverse sectional view through the grease cup.

Figure 2 is a horizontal sectional view taken on line 2-2 of Figure 1.

45 Figure 3 is a horizontal sectional view taken on line 3-3 of Figure 1.

Figure 4 is a horizontal sectional view taken on the line 4-4 of Figure 1.

50 Referring to the drawing the numeral 1 designates the body of the grease cup having a chamber 2 therein. The lower end of the body 1 is provided with a discharge port 3 having a valve seat 4, with which the valve 5 of a hollow valve stem 6 cooperate for regulating the amount of lubricant allowed 55 to pass through the discharge port 3. The

upper end of the valve stem 6 is threaded at 7 into an enlargement 8 carried by the under side of the cup cap 9, and has its chamber 10 in communication with the intake port 11 extending through the cap 9, 60 whereby lubricant forced into the device by a grease gun attached at 12 to the fitting 13 will be forced past the spring actuated valve 14 through intake port 11, chamber 10, and will be discharged into the lower 65 portion 2^a of the chamber 2 through the discharge ports 15 in the valve stem and below the piston 16, which is slidably mounted on the valve stem 6 in engagement with the inner periphery of the body 1 of the cup. 70 As the lubricant is forced into the portion 2^a of the cup chamber, under pressure by a grease gun or pump, the piston 6 is forced upwardly against the action of the helical spring 17, which spring is interposed between the upper side of the piston 16 and the under side of the cap 9, therefore it will be seen that the cup is filled without removing the cover and by the use of a grease gun. 75 It will also be seen when the grease gun is 80 removed from the connection at 12, the spring actuated valve 14 will immediately seat, thereby preventing escape of lubricant upwardly and the helical spring 17 will exert a downward pressure on the piston 16 85 and discharge lubricant as consumed to a bearing or otherwise through the discharge port 3 in a quantity according to the position of the valve 5 in relation to the valve seat 4.

90 The cup cap is threaded at 16 on the upper end of the body 1 and has pivotally mounted at 17 in a recess 18 in one side thereof a lever 19, the nose 20 of which extends through an aperture 21 in the flange 22 of the cap and is received in one 95 of a plurality of recesses 23 in the outer periphery of the body 1, thereby holding the cap 7 in various adjusted positions. Lever 19 is normally held in operative position by means of a coiled spring 24. It will be seen that by rocking the lever 19 and moving its nose 20 out of the recess 23, the cap will be unlocked, and the same can be rotated to various positions for adjusting 100 the valve 5 carried thereby in relation to the valve seat 4 and discharge port 3, therefore the amount of lubricant discharged from the cup may be regulated and after an 105 adjustment upon release of the lever 19 it 110

will be received in one of the recesses 23 and will positively lock the cover against rotation incident to jar and the like. The 5 slideable piston 16 comprises spaced discs 24, between which are clamped by means of the screws 25 flexible washers 26 and 27. The washer 26 is provided with a downwardly extending flange 28, which engages the inner periphery of the body 1 and the 10 washer 27 with a downwardly extending flange 29, which engages the outer periphery of the hollow valve stem 6, thereby positively preventing lubricant from passing upwardly past the piston at all times.

15 From the above it will be seen that a lubricant cup is provided, which is simple in construction, will not require the opening of the cup for filling, will automatically feed lubricant, and the valve 5 is carried by 20 the cover which may be positively adjusted to various positions for regulating the amount of lubricant forced from the cup by the spring actuated piston.

The invention having been set forth what is claimed as new and useful is:—

25 A grease cup comprising a chambered casing having a discharge port at one end thereof, a cap at the other end and having an intake port therethrough, a check valve adjacent said intake port, a chambered 30 valve stem carried by the cap and having its chamber in communication with the intake port and in communication with the casing chamber adjacent the discharge port, a valve carried by said valve stem and co-operating with a valve seat in communication with the discharge port, a piston slidably mounted on said valve stem and engaging the wall of the casing chamber, a helical 35 spring interposed between said cap and piston, the convolutions of said helical spring being receivable within each other.

40 In testimony whereof I hereunto affix my signature.

LOUIS A. LE DOUX.
